CLAIM

The new, original, and ornamental design for a dual pack wrapper, as shown and described.

DESCRIPTION

FIG. 1 is a front elevational view of a dual pack wrapper showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The phantom-line and/or broken-line depictions in the drawings are shown for environmental and illustrative purposes only, and form no part of the claimed design of the present invention.
